(57) **CLAIM**

The ornamental design for a razor case, as shown and described.

DESCRIPTION

FIG. 1 is a top front left perspective view of a razor case showing my new design;

FIG. 2 is a top plan view thereof;

FIG. 3 is a left side elevational view thereof, the right side elevation being a mirror image thereof;

FIG. 4 is a bottom plan view thereof;

FIG. 5 is a rear elevational view thereof;

FIG. 6 is a front elevational view thereof; and,

FIGS. 7-12 correspond respectively to FIGS. 1-6 except that the cover of the case is shown in open condition.
